UNITED STATES PATENT OFFICE.

ARTHUR C. HAYDEN, OF BROCKTON, MASSACHUSETTS.

RAZOR-STROPPER.

977,868.

Specification of Letters Patent.

Patented Dec. 6, 1910.

Application filed September 26, 1910. Serial No. 583,826.

To all whom it may concern:

Be it known that I, ARTHUR C. HAYDEN, a citizen of the United States, residing at Brockton, in the county of Plymouth and 5 State of Massachusetts, have invented a new and useful Razor-Stropper, of which the following is a specification.

This invention relates to grinding and polishing, and more especially to the strops 10 and hones used for sharpening safety razor blades; and the object of the same is to produce a small and convenient device by which almost any type of safety razor blade can be honed and stropped quickly.

15 To this end the invention consists in the details of construction set forth below and shown in the drawings, wherein,—

Figure 1 is a perspective view of the strop and hone complete. Fig. 2 is a plan view; 20 and Fig. 3 is a longitudinal section on the line 3—3 of Fig. 2. Fig. 4 is an enlarged side elevation of one end of the device showing the carriage. Fig. 5 is a cross section on the line 5—5 of Fig. 4. Figs. 6 and 7 are 25 diagrammatic illustrations showing different windings of the belt for a purpose to be described below; and Fig. 8 is a sectional detail of the blade holder in the carriage.

The frame of this device is substantially 30 rectangular as will be seen in Fig. 2 and comprises two end bars 1 connected near their extremities by side bars 2, the connection here shown being by means of ears 3 at the ends of the side bars bent over into 35 notches 4 near the ends of the end bars. The latter have threaded eyes 5 at their centers for handles 6 of which one is shown although there may be two. The extremities of the end bars project beyond the side bars and 40 carry tracks 9, here shown as round rods extending through eyes 7 in said extremities and receiving nuts 8 whereby the tracks can be removed, although any other suitable form of attachment might be employed as 45 long as the tracks stand parallel with and at a slight distance from the side bars of the frame.

Midway of the length of the frame bearings 10 rise rigidly from its side bars, and 50 between them is pivoted a shaft 11 on which is fixed a pulley 12 near one end of the shaft. Inside the adjacent side bar 2 near its ends are journaled pulleys 13, and over the latter passes a flexible and in some cases an elastic 55 cable 14 which is given a coil around the pulley 12 and which is provided with hooks

15 at its extremities to detachably engage the carriage hereinafter described. Said shaft 11 has secured rigidly thereto a blade holder 16 (see Fig. 8) of such a shape that it will 60 detachably receive a safety blade 17 of any of the ordinary constructions now on the market.

The carriage is by preference stamped from a single piece of sheet metal initially 65 rectangular in general contour and with eyes 20 at its corners which are bent up into parallelism as shown, and those at each side of the carriage embrace and are adapted to slide upon one of the tracks 9 as will 70 be clear. Thence the metal of the carriage passes inward beneath the side bar 2 as at 21, is bent upward as at 22 inside but out of contact with said side bar, and is then bent inward as at 23 and extends across 75 within the frame, being by preference made rather open as shown at 24 for the sake of lightness. Secured upon a diagonal bar across the carriage is the strop 25, and it is to be understood that although I have shown 80 this as fixed thereon it may be removably attached thereto so that a hone or other abrading surface could be substituted when desired. In any event provision will be made to attach a new strop when necessary, 85 and no claim is laid to the means of attachment although I consider it important that it shall extend obliquely across the carriage. 26 is a handle depending from the carriage by which the latter is manipulated, and like 90 the handle 6 this may be removed so that the whole device can be reduced to small compass. In one of the lower bars 21 of the carriage is formed a pair of eyes 27 with 95 which the hooks 15 engage, as best seen in Fig. 4. All parts are preferably of sheet metal excepting the strop and the hone when the latter is used, and the proportions and details are unimportant.

In use, the parts are assembled as best 100 seen in Fig. 1 and the cable is wound around the main pulley 12 as shown in that view and in Fig. 6. The operator takes the handle 6 in one hand and the handle 26 in the other, and moving the latter to the right 105 the carriage draws the cable 14 around the left hand idle pulley 13 and turns the pulley 12 in a direction to throw the blade 17 over as shown by the arrow; so that as the carriage moves beneath the blade holder, the latter revolves and carries the blade with it and by the time the front end of the strop 110

25 has passed under the blade holder the blade has been turned over to a position where it is thrown down upon the strop and held there as the cable slips around the 5 main pulley 12. The forward movement of the carriage is continued until checked by the right hand idle pulley 13, where a reversal of the operation takes place and in the movement of the carriage to the left 10 the blade is thrown over in the opposite direction and its other side is wiped across the strop 25. Without any practice the most inexperienced person can thus quickly strop a razor. The construction of the 15 blade holder is such that almost any of the common types of safety blades can be inserted therein from that end of the clamp 16 which is remote from the pulley 12, and after sharpening the blade it is drawn from 20 place and used in the ordinary manner.

Fig. 7 shows diagrammatically how the cable can be given a reverse winding around the main pulley 12 which of course will cause a reverse movement of the blade holder 25 and the blade it carries. It is hardly necessary to illustrate how a hone or abrading surface may be substituted for the strop 25, but when this is done and it is desired to push the edge of the blade across this 30 surface rather than to draw it across a soft surface such as the strop, it will be clear that the winding of the belt 14 as illustrated in Fig. 7 will cause the opposite movement of the blade holder and blade as the carriage 35 is reciprocated.

What is claimed as new is:—

1. In a razor strop, the combination with a frame having bearings rising from it, and idle pulleys journaled within it near its 40 ends; of a shaft journaled in said bearings and carrying a blade holder, a carriage sliding within the frame and supporting a strop, a cable attached to the carriage and extending thence in either direction around 45 the idle pulleys and with its center coiled around said shaft, and means for reciprocating the carriage relatively to the frame.

2. In a razor strop, the combination with a frame comprising side bars and end 50 bars and tracks carried by the end bars par-

allel with and spaced from the side bars, bearings rising from the mid-length of the side bars, and idle pulleys mounted inside one side bar near its ends; of a shaft journaled in said bearings and carrying a blade 55 holder, a pulley fast on the shaft in line with the idle pulleys, a carriage having eyes at its extremities sliding on said tracks and a body between them supporting a strop, and a cable coiled around and adapted to 60 slip upon said pulley on the blade holder shaft and extending thence over said idle pulleys and connected with the carriage.

3. In a razor strop, the combination with a rectangular frame comprising end 65 bars having eyes at their extremities and notches just inside the eyes, side bars having ears at their extremities engaging said notches, and tracks consisting of round rods standing parallel with the side bars and extending through the eyes of the end bars, and nuts on their ends, said end bars having eyes at their mid-length; of a handle adapted to engage either of the last-mentioned eyes, 70 a carriage slidably mounted on said tracks 75 and carrying a strop between said side bars, a handle on the carriage, and means for holding the blade against the strop with yielding pressure.

4. In a razor strop, the combination 80 with a frame comprising side bars and end bars, bearings rising from the side bars, and idle pulleys mounted inside one side bar near its ends; of a shaft journaled in said bearings and carrying a blade holder, a pulley 85 fast on the shaft in line with the idle pulleys, a carriage sliding within the frame and supporting a strop, a cable coiled around and adapted to slip upon said pulley on the blade holder shaft and extending thence over 90 said idle pulleys, and hooks connecting its ends with the carriage.

In testimony that I claim the foregoing as my own, I have hereto affixed my signature in the presence of two witnesses.

ARTHUR C. HAYDEN.
